ANTISKID SHOE ATTACHMENT

Charles F. Mutter, Brooklyn, N. Y.

Application October 28, 1938, Serial No. 237,409

8 Claims. (Cl. 36—7.6)

This invention relates to new and useful improvements in a non-skid shoe attachment.

More specifically, the invention proposes the construction of a non-skid shoe attachment characterized by the provision of a flat body for engagement upon a shoe and having a plurality of blades attached obliquely across the bottom thereof in a particular manner and provided with serrated bottom edges for gripping ice or snow to assist one in walking.

Still further the invention proposes the provision of a plurality of bars mounted on said flat body and extended substantially at right angles to said blades for assisting in rigidly holding said blades in position.

Another object of this invention is the provision of fibre members mounted on the sides of said blades along said serrated bottom edges with the bottom edges of said fibre members being flush with the bottom edges of said blades in a particular manner to protect one's hands or fingers from coming in direct contact therewith.

Still further the invention proposes the provision of a flat body for attachment on the sole of a shoe and having a plurality of spring pressed plungers mounted therein and having their bottoms serrated and extended from said body to engage the snow or ice.

For further comprehension of the invention, and of the objects and advantages thereof, reference will be had to the following description and accompanying drawing, and to the appended claims in which the various novel features of the invention are more particularly set forth.

35 In the accompanying drawing forming a material part of this disclosure:

Fig. 1 is a side elevational view of a shoe having a non-skid shoe attachment constructed according to this invention, mounted thereon.

40 Fig. 2 is a bottom plan view of the non-skid shoe attachment per se.

Fig. 3 is a perspective view of one of the blades, per se, showing a portion of one of the bars associated therewith.

45 Fig. 4 is a sectional view on the line 4—4 of Fig. 3.

Fig. 5 is an elevational view of a portion of one of the blades per se.

50 Fig. 6 is an enlarged sectional view on the line 6—6 of Fig. 3.

Fig. 7 is a partial perspective view of one of the bars per se.

Fig. 8 is a sectional view on the line 8—8 of Fig. 7.

55 Fig. 9 is an elevational view of one of the blades

constructed according to a modification of the invention.

Fig. 10 is a view similar to Fig. 1 but illustrating a further modification of the invention.

Fig. 11 is a sectional view on the line 11—11 of Fig. 10.

Fig. 12 is a view similar to Fig. 1 but illustrating a still further modification of the invention.

The non-skid shoe attachment, according to this invention, comprises a flat body 10 for extending across the sole and heel of a shoe 11. The flat body 10 is constructed of heavy cloth material or other similar material and is provided with a means for supporting it in an extended position across the sole and heel. This means comprises a toe strap 12 consisting of a toe strap section 12^a attached to one side of the body 10 and engageable across the toe of the shoe and upon a second toe strap section 12^b attached to the other side of the body 10.

Complementary snap fasteners 13 are provided upon adjacent faces of the strap sections 12^a and 12^b for holding the front end of the body in position on the sole of the shoe 11. A heel engaging portion 14 is provided on the back end of the body 10 and is engageable upon the heel of the shoe 11. A strap 15 is provided for engaging around the shoe in the vicinity of the ankle and comprises a strap section 15^a attached to one side of the heel portion 14 and engageable upon a strap section 15^b mounted on the other side of the heel portion 14. Complementary snap fastener elements 16 are provided on the strap sections 15^a and 15^b for supporting the back end of the flat body 10 upon the heel of the shoe 11.

40 A plurality of blades 17 are attached obliquely upon the bottom of the body 10 and have serrated bottom edges 17^a for engaging snow or ice on the streets for assisting one in walking. The blades are formed at their upper ends with oppositely extending lugs 17^b having openings 18 through which rivets 19 are adapted to be passed for holding the blades 17 in position upon the bottom face of the flat body 10.

45 A plurality of bars 20 are mounted on the flat body 10 substantially at right angles to the blades 17 for assisting in maintaining the blades rigidly in position. The bars 20 are also formed with lugs 20^a directed in opposite directions and formed with openings 21 through which rivets 22 may be passed for attaching the bars to the bottom of the flat body 10. The bottom edge of the bars 20 are formed with inwardly extending cutouts 20^b which are adapted to engage complementary cutouts 17^c formed in the top edges of the blades 55

17 where the bars and blades cross for permitting them to be formed of continuous strips and still pass each other. An inspection of Fig. 4 will reveal that the sides of the cutouts 20^b formed 5 in the bars 20 engage upon either side of the blades 17 for assisting in maintaining them in their vertical position with relation to the flat body 10.

A plurality of fibre members 23 are mounted 10 on the sides of the blades 17 along the serrations 17^a. The bottom edges of the fibre members 23 are flush with the bottom edges of the blades 17 for partially covering the same to prevent one's hands and fingers from contacting there- 15 with while the shoe attachment is being engaged upon one's shoe. These fibre members 23 are in the form of ropes or similar members and are maintained in position on the sides of the blades by means of extending lugs 24 stamped from the 20 vertical portions of the blades and which are engaged around the fibre members 23. The ends 24^a of the lugs 24 are engaged into the side of the fibre members for rigidly maintaining them in position upon the blades 17.

25 The operation of this device is as follows:

The sole and heel of one's shoe is rested on the top face of the flat body 10 and the straps 12 and 15 are engaged around the shoe for maintaining the flat body in a position extended across 30 the sole and heel of one's shoe. The fibre members 23, while the attachment is being engaged upon one's shoe, will remain flush with the bottom edge of the blades 17 to prevent the serrations 17^a from cutting one's hands and fingers. However, when the weight of the body is rested upon the 35 flat body 10 it will cause the serrations 17^a to be slightly extended beyond the bottom edge of the fibre members 23 by slightly compressing the same against the lugs 24 to permit the serrations 17^a 40 to engage the snow and ice to assist one in walking thereon.

According to the modification of the invention shown in Fig. 9 the construction of the non-skid shoe attachment is similar to that previously 45 described, distinguishing therefrom merely by the inclusion of a strand of cord or wire 25 which is wound upon each of the fibre members 23 for providing additional elements for assisting one in walking upon ice or snow. In this form of 50 the invention when the weight of the body is rested upon the flat body 10 the fibre members will be compressed and the cord or wire 25 will also assist the serrations 17^a in gripping the ice or snow. In other respects this form of the 55 invention is similar to the previous form.

According to the modification of the invention shown in Figs. 10 and 11 the non-skid shoe attachment includes a flat body 26 having a plurality of inwardly extending openings 26^a. The 60 flat body 26 is adapted to be extended across the sole of one's shoe and be maintained in position by means of a toe strap 27 which has its ends attached to opposite sides of the flat body 26 by means of nails or rivets 28.

65 A plurality of plungers 29 are slidably engaged into the openings 26^a and extend inwards from the bottom of the body 26. Each of the plungers 29 is formed with a reduced extension 29^a and a plate 30 is extended across the bottom of the 70 body 26 and is maintained in position by means of screws 31. The plate 30 is formed with a plurality of openings 30^a through which the reduced ends 29^a of the plungers 29 extend. The bottom face of the reduced portions 29^a are formed with 75 a plurality of serrations 29^{aa} which are adapted

to engage the snow or ice for assisting one in walking thereon. Springs 32 operate between the top faces of the plungers 29 and the upper end of the openings 26^a for urging the plungers 29 into their extended positions.

5 In Fig. 12, the flat body 10' is extended across the sole of a lady's shoe 11' with high heel 11^a and held thereon by a strap 12 or any other suitable manner. This flat body includes the serrated blades 17 and the fibre members 23. Another 10 flat body 26' is held by strap 12' or the like and includes a spring pressed plunger 29 with serrations 29^{aa} as previously described. This form 15 of the invention is especially arranged for high heeled shoes.

It is to be understood that this non-skid device may be secured on all types and sizes of shoes, including rubber shoes and the serrated members are preferably made of aluminum or other non-corrosive material while the fibre members may 20 be of Jude rope, canvas or like materials.

While I have illustrated and described the preferred embodiments of my invention, it is to be understood that I do not limit myself to the precise constructions herein disclosed and the 25 right is reserved to all changes and modifications coming within the scope of the invention as defined in the appended claims.

Having thus described my invention, what I 30 claim as new, and desire to secure by United States Letters Patent is:

1. A non-skid shoe attachment, comprising a flat body for extending across the sole and heel of a shoe, means for mounting said body on said shoe, a plurality of blades attached obliquely on the bottom of said body and having serrated bottom edges for gripping ice, snow, etc., on the street, a plurality of bars mounted on said flat body for assisting in rigidly holding said blades, and fibre members mounted on the sides of said 40 blades along said serrations.

2. A non-skid shoe attachment, comprising a flat body for extending across the sole and heel of a shoe, means for mounting said body on said shoe, a plurality of blades attached obliquely on the bottom of said body and having serrated bottom edges for gripping ice, snow, etc., on the street, a plurality of bars mounted on said flat body for assisting in rigidly holding said blades, and fibre members mounted on the sides of said 50 blades along said serrations, said flat body being constructed of heavy cloth material.

3. A non-skid shoe attachment, comprising a flat body for extending across the sole and heel of a shoe, means for mounting said body on said shoe, a plurality of blades attached obliquely on the bottom of said body and having serrated bottom edges for gripping ice, snow, etc., on the street, a plurality of bars mounted on said flat body for assisting in rigidly holding said blades, and fibre members mounted on the sides of said 55 blades along said serrations, said means comprising a strap for engaging over the toe of one's shoe, and a strap for engaging over one's shoe in the vicinity of one's ankle.

4. A non-skid shoe attachment, comprising a flat body for extending across the sole and heel of a shoe, means for mounting said body on said shoe, a plurality of blades attached obliquely on the bottom of said body and having serrated bottom edges for gripping ice, snow, etc., on the street, a plurality of bars mounted on said flat body for assisting in rigidly holding said blades, and fibre members mounted on the sides of said 70 blades along said serrations, said blades being 75 constructed of metal and having oppositely di- 75

rected lugs formed with openings through which rivets may be passed for attaching said blades to said body.

5. A non-skid shoe attachment, comprising a flat body for extending across the sole and heel of a shoe, means for mounting said body on said shoe, a plurality of blades attached obliquely on the bottom of said body and having serrated bottom edges for gripping ice, snow, etc., on the street, a plurality of bars mounted on said flat body for assisting in rigidly holding said blades, and fibre members mounted on the sides of said blades along said serrations, said bars having their top edges formed with oppositely directed lugs having openings through which rivets may be passed for attaching said bars to said body.

6. A non-skid shoe attachment, comprising a flat body for extending across the sole and heel of a shoe, means for mounting said body on said shoe, a plurality of blades attached obliquely on the bottom of said body and having serrated bottom edges for gripping ice, snow, etc., on the street, a plurality of bars mounted on said flat body for assisting in rigidly holding said blades, and fibre members mounted on the sides of said blades along said serrations, said blades and said bars being extended substantially at right angles to each other, and said blades and bars being formed with cooperating cutouts at their crossing

points with the sides of the cutouts formed in said bars engaging the sides of the blades below the cutouts formed in said blades for maintaining said blades in position.

7. A non-skid shoe attachment, comprising a flat body for extending across the sole and heel of a shoe, means for mounting said body on said shoe, a plurality of blades attached obliquely on the bottom of said body and having serrated bottom edges for gripping ice, snow, etc., on the street, a plurality of bars mounted on said flat body for assisting in rigidly holding said blades, and fibre members mounted on the sides of said blades along said serrations, said fibre members being lengths of rope or other similar material.

8. A non-skid shoe attachment, comprising a flat body for extending across the sole and heel of a shoe, means for mounting said body on said shoe, a plurality of blades attached obliquely on the bottom of said body and having serrated bottom edges for gripping ice, snow, etc., on the street, a plurality of bars mounted on said flat body for assisting in rigidly holding said blades, and fibre members mounted on the sides of said blades along said serrations, said fibre members having a strand of cord or wire wound there-around for engaging the ice or snow to assist the serrations on said blades in gripping the same.

CHARLES F. MUTTER.
